Primary Examiner — Mark Goodwin(74) *Attorney, Agent, or Firm* — Ward and Smith, P.A.(57) **CLAIM**

The ornamental design for a rake prong, as shown and described.

DESCRIPTION

FIG. 1 is a perspective view of a rake prong showing my new design, the threaded portion of FIGS. 1-3, 6, and 7 being shown broken away to indicate indeterminate length;

FIG. 2 is a right side elevation view thereof the left side view being a mirror image thereof;

FIG. 3 is a front elevation view thereof the rear view being a mirror image thereof;

FIG. 4 is a top plan view thereof;

FIG. 5 is a bottom plan view thereof;

FIG. 6 is a perspective view of another embodiment of a rake prong showing my new design;

FIG. 7 is a right side elevation view thereof the left side view being a mirror image thereof; and,

FIG. 8 is a top plan view thereof.
